(57) **CLAIM**

The ornamental design for a fluid container as shown and described.

DESCRIPTION

FIG. 1 is a perspective view of a fluid container of our new ornamental design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a perspective view thereof in a condition of use.

The broken lines in the drawings show portions of the fluid container and form no part of the claimed design.

1 Claim, 8 Drawing Sheets
